UNITED STATES PATENT OFFICE.

JOSEPH DE FRANCISCI, OF BROOKLYN, NEW YORK, ASSIGNOR TO CONSOLIDATED MACARONI MACHINE CORPORATION OF NEW YORK, N. Y., A CORPORATION OF NEW YORK.

MACARONI PRESS.

Original application filed October 31, 1924, Serial No. 746,920. Divided and this application filed August 21, 1925. Serial No. 51,564.

This invention is a macaroni press, and it pertains more particularly to a hydraulic motor for controlling the movement of the press-plunger and for precluding leakage 5 of the motive fluid from the high pressure end of the power cylinder.

The invention of this application is a division of a prior application filed by me on October 31, 1924, Serial No. 746,920.

10 One part of the invention is a novel packing for effectually precluding the leakage of the motive fluid from the high pressure end of the power cylinder.

Another part of the invention is an improved mechanism operated by the power plunger for effecting the automatic reversal 15 in the direction of movement of the power plunger as it approaches or reaches the limit of its movement.

20 Other functions and advantages of the invention will appear from the following description taken in connection with the drawings, wherein

Figure 1 is a view partly in elevation and 25 partly in vertical section of a hydraulic motor for a macaroni press embodying my invention.

Figure 2 is a vertical sectional view through 30 the motor illustrating the fluid pressure packing for the high pressure end of the motor cylinder.

Figure 3 is a detail view of the plunger controller illustrating the parts in the reverse position of Figure 1.

35 Mounted in a frame A is a power cylinder B, within which operates a power plunger C, the diameter of which for a part of its length is slightly less than the internal diameter of said power cylinder, thus producing an intermediate annular space c. At its upper end, the plunger is provided with a piston head b having packing rings b', b'', of any suitable character. At the lower end, said plunger protrudes below the power cylinder 40 and is provided with a flange c', with which co-operates means for shifting a valve mechanism.

The upper part of the power cylinder is 50 counter-bored to produce a pressure chamber D, the internal diameter of which exceeds the internal diameter of the working chamber in which operates the power plunger C. This enlargement of the pressure chamber D

provides a seat or shoulder d on which rests a pressure head d'. This head carries an outlet valve d'', and a spring pressed inlet valve d', said valves controlling the flow of fluid through passages d' and d'', respectively. As shown, the outlet valve d'' is retained with a suitable cage, whereas the inlet valve is in the form of a needle valve, but any type of valve may be used.

The pressure cylinder is itself closed at its top by a cylinder head E, which is shown as having a depending annular flange e, the diameter of which is less than the internal diameter of the pressure chamber D above the pressure head d' by which the pressure chamber is separated from the working chamber 70 of the power cylinder. This depending flange enters the pressure chamber, and said flange is spaced from the annular wall of said chamber. A packing e' is interposed between the flange e and the wall of said chamber, said packing being compressed between top and bottom metal rings e'', e''', by clamping bolts e'' which are threaded through the cylinder head and engage the upper ring e''. The lower ring e''' is of sectional construction, 80 and it is received within a circumferential groove e'', cut in the outer wall of the head flange.

The construction at the upper part of the power cylinder herein described constitutes 85 an important part of my invention, and embodies a structure possessing great strength and which acts effectively to seal the pressure chamber against fluid leakage under high pressure working conditions.

The power cylinder B, and a plurality of dough cylinders F connected therewith by the sleeve f'' are supported as a unit on heavy springs H, H', which loosely encircle the frame posts A and rest upon collars h, h', 95 fixedly attached to said frame posts, said springs bearing upwardly against side extensions B', B'', of the power cylinder B. The cylinder head E is retained in position by collars h'', h''', fixed to the posts A of the press frame.

The power cylinder and the dough cylinders are free to have a limited vertical travel on the press frame upon the compression of the heavy coiled springs H, H', prior to the 105 downward power stroke of the plunger C, as a result of which the dough cylinder F or

F' is movable downward by fluid pressure with respect to a die K , so that the beveled rim K^2 enters between the die and the dough cylinder prior to the descent of the power 5 plunger, for precluding the dough from passing through the joint between the cylinder and the extruding die or its die-block.

The plunger C is moved up and down within the power cylinder B by fluid pressure, and for this purpose I employ a single reversible valve O and pipe connections m , m' , leading from said valve O to the upper part and the lower part, respectively, of the power cylinder. In the neutral position of 10 the valve O , indicated by the dotted line x in Figure 1, no fluid pressure flows through the valve to either end of the power cylinder; with the valve moved to the full line position x' of Figure 1, fluid flows through pipe m to the upper part of the cylinder for applying 15 pressure to the plunger and thus impart the power stroke thereto; but with the valve shifted to the dotted line position x^2 in Figure 1, the valve controls the flow of pressure 20 by shutting off the flow through pipe m and directing the flow through pipe m' to the lower part of the cylinder for raising the plunger at an increased speed as compared 25 with the speed of movement on the descending power stroke of the plunger.

The control valve O is provided with an operating handle o , to which is pivoted a rod O' , extending upwardly to and above the lower end of the power cylinder B , said 30 rod being provided at its upper end with a stop o' . An angular latch P is pivoted at p to the press frame or the cylinder B , one arm of this latch is fitted loosely on the valve rod O' for engagement with the stop o' 35 thereof, whereas the other depending arm of the latch is provided with a notch p^2 and with protruding cam face p^2 , see Figures 1 and 3. To the pivoted angular latch P is connected a coiled spring P' . In directing 40 the fluid into the upper part of the power cylinder B , the free notched end of the angular latch is engageable with stop member Q shown as a pivoted element controlled by a spring q , and this stop member co-operates 45 with the latch P for retaining the spring P' under tension, and locking the valve rod O' and the valve O in the position to direct the flow of fluid to the upper part of the power cylinder. A latch releasing member R in the 50 form of a trip pin co-operates with the latch P , said trip pin being slidable in the power cylinder at the lower part thereof. The outer end of the trip pin is adapted for contact with the angular latch P , whereas the 55 inner end of the trip pin when in a set position, extends into the space c between the plunger B and the cylinder wall, so that said inner end of the trip pin is in the path of the beveled face b^{10} of the plunger. On the 60 power stroke of the plunger, it is forced

downwardly by the fluid pressure, and the trip pin and the latch remain in the position of Figure 1, but as the plunger approaches the limit of its downward travel, the trip pin is engaged by the bevel face of the plunger, 70 the effect of which is to press the trip pin outwardly and thus shift the latch for its notched lower end to be disengaged from the stop member Q , and thereupon the spring expands for pulling the latch and the valve rod upwardly, as in Figure 3, the result of 75 which is to shift the valve O , and thus reverse the flow of fluid by closing the flow to pipe m and opening the flow to pipe m' , whereby the control valve is reversed automatically by devices responsive to the travel 80 of the plunger.

After a dough cylinder is charged, the control valve is shifted to the full line position of Figure 1 for directing the motive fluid through pipe m into the pressure chamber D above the pressure head d . The fluid fills the chamber D and the continued supply of fluid increases the pressure within the chamber, the pressure being accumulated or built up in said chamber until the resistance of the springs H , H' , is overcome, the result of which is to cause the power cylinder and the dough cylinders to slide downwardly for a limited distance. The lower end of the dough cylinder F or F' is thus seated by the energy of fluid pressure built up in the chamber D so as to secure a sealed connection between said dough cylinder and the extruding die before the motive fluid is admitted 90 to the working chamber of the power cylinder. The pressure continues to accumulate within the chamber D until it overcomes the resistance of the spring associated with the needle valve, and thus the motive fluid is admitted to the working chamber of the power cylinder to force the plunger downward. The descent of the plunger upon the material extrudes the latter through the die, and as the plunger approaches the lower limit of its movement within the power cylinder, the beveled cam face b^2 contacts the inner end of the trip pin, forcing it outwardly and causing the angular latch to disengage it 100 from the detent, whereupon the spring lifts the angular latch and the valve rod to thereby shift the control valve, the result of which is to arrest the flow of liquid through pipe m , and thus direct the liquid through pipe m' into the lower part of the power cylinder. The plunger is raised by the energy of the liquid supplied to the space c , whereupon the liquid present in the cylinder flows through the check valve d^2 and thence by chamber D through pipe m . As shown, the upward travel of the plunger brings the lower flange c^4 into contact with a trigger T , which acts on a collar t of the valve rod to shift the control valve to a neutral position, thus 110 arresting the operation of the press. 115

In my invention the power cylinder is provided with a chamber D which may be said to be separate from the working chamber. This separate chamber D is usually isolated from the working chamber by the head d', although said head may be omitted, but in practice it is used. Said separate chamber D, herein referred to as the pressure chamber, is of greater cross sectional area than the working chamber of the power cylinder, and this separate chamber is useful in that it affords a space within which the pressure is built up or accumulated for the purpose of imparting the downward limited travel to the power cylinder and the dough cylinders, whereby the desired tight connection between the dough cylinder and the extruding die is obtained prior to the downstroke of the plunger.

In my invention a characteristic feature consists in the use of cushion springs H, H', or their equivalents for yieldably supporting the power cylinder and the dough cylinders connected therewith. Again, the power cylinder is provided with a pressure chamber D, the diameter of which exceeds the internal diameter of the working chamber in which travels the power plunger C. When the press is in service, the pressure of the fluid is "built up" or accumulates in the chamber D until the resistance of the springs H, H', is overcome, and thus a downward travel, to a limited extent, is imparted to the connected power and dough cylinders, the effect of which is to seat the dough cylinder upon the extruding die and to attain a sealed connection therebetween prior to the descent of the power plunger.

Having thus fully described the invention, what I claim as new and desire to secure by Letters Patent is:

1. In a motor for a press, a pressure cylinder and a plunger, a cylinder head provided with a depending flange spaced relatively to the cylinder and forming a space for a packing which is exposed to the pressure of motive fluid, a pressure head seated within the cylinder and producing a chamber within which the pressure of motive fluid is adapted to be built up, said pressure head having an inlet port to the pressure cylinder, and means for supplying motive fluid to the pressure chamber.

2. In a motor for a press, a power cylinder head provided with means for retaining a packing, a plate seated within said power cylinder to produce a chamber within which may be built up the pressure of a motive fluid supplied to said chamber, said packing being exposed to fluid pressure within the chamber, said pressure plate being provided with an inlet to the working chamber of the power cylinder and an exit port from said chamber, means for feeding a motive fluid to said pressure chamber of the power cyl-

inder, and a plunger operable within said power cylinder.

3. In a motor for a press, a power cylinder, a head for said power cylinder, said head having means for retaining a packing, a plate positioned fixedly within said power cylinder and producing a chamber within which may be built up the pressure of a motive fluid adapted to be supplied to said chamber, a packing co-operable with said head and exposed to the pressure of the motive fluid, a plunger, and means carried by said head for controlling the flow of motive fluid from the chamber to the power cylinder.

4. In a motor for a press, or like apparatus, a power cylinder mounted for slidable movement, a pressure chamber within which a motive fluid is adapted to accumulate to a determined pressure, said pressure chamber including a member exposed to fluid pressure and operable for imparting sliding movement to said power cylinder, means opposing the sliding movement of the power cylinder, and means for admitting motive fluid to the power cylinder when the pressure within the pressure chamber exceeds the determined limit.

5. In a motor for a press, or like apparatus, a slidable power cylinder having a working chamber, means affording resistance to the sliding motion of the power cylinder, a pressure chamber unitary with the power cylinder within which pressure chamber a motive fluid is adapted to flow for attaining a determined pressure, said pressure chamber including a member exposed to fluid pressure and operable for imparting sliding motion to the power cylinder, and means for feeding motive fluid from the pressure chamber to the working chamber when said motive fluid attains a determined pressure within the pressure chamber.

6. In a motor for a press, or like apparatus, a power cylinder provided with a working chamber and with a pressure chamber the cross sectional area of which exceeds the corresponding area of the working chamber, a plunger operable within the working chamber, and valved means for establishing communication between the pressure chamber and the working chamber, said valved means being closed during the accumulation of motive fluid within the pressure chamber and said valve being operated by the motive fluid when it reaches a determined pressure within the pressure chamber, whereby the motive fluid is supplied to the working chamber for actuating the plunger therein.

7. In a motor for a press, or like apparatus, a power cylinder provided with a working chamber and a pressure chamber the cross sectional area of which exceeds the corresponding area of the working chamber, a plunger operable within the working chamber, a valved communication intermediate the pressure chamber and the working chamber

for admitting a fluid to the latter chamber, whereby the plunger is actuated in one direction, and a separate valved connection for the egress of motive fluid from the working chamber on the return movement of said plunger.

8. In a motor for a press or other apparatus, a power cylinder, a plunger provided with a cam face, a control valve operable at will when in a neutral position and connected for feeding a motive fluid to said cylinder whereby said plunger is actuated in both the power stroke and the return stroke by a motive fluid flowing from a source of supply through said control valve, latching means for locking said control valve in an operative position during the period of flow of the motive fluid on the power stroke of the plunger, means operated by the plunger-cam-face as the plunger approaches the limit of its power stroke, for reversing the control valve, whereby the flow of motive fluid through said control valve is diverted from one end of the cylinder to the other end thereof and the motive fluid is effective in imparting the return stroke to said plunger, and separate valve-shifting means operable on the return movement of the plunger for moving said control valve to a neutral position whereby the return travel of the plunger is arrested by the cessation in the flow of the motive fluid.

9. In a motor for a press or other apparatus, a power cylinder, a plunger provided with a cam face, a control valve operable at will when in a neutral position and connected for feeding a motive fluid to said power cylinder for effecting the power stroke and the return stroke of said plunger, a latch member connected operatively with said control valve, a detent co-operable with said latch member for locking said control valve during the power stroke of said plunger, a release member slidably through the cylinder wall and positioned in the path of the

cam face of said plunger to be actuated by the travel of the plunger as the latter approaches the limit of movement in one direction, said release member acting on the latch member for effecting the disengagement of said latch from the detent, means for reversing the control valve on the release of the latch member whereby the flow of motive fluid is diverted from one end of the power cylinder to the other end thereof and the return stroke of the plunger is effected by the pressure of motive fluid, and means operable directly by the plunger for shifting the control valve to a neutral position whereby the plunger is arrested by the cessation in the flow of motive fluid through said control valve.

10. In a motor for presses and other apparatus, a power cylinder, a plunger provided at an exposed end with a shoulder, a control valve operable at will when in a neutral position and connected for feeding a motive fluid to said cylinder for effecting the power stroke and the return stroke of said plunger by the energy of the motive fluid, means for locking said valve during the power stroke of the plunger, means for releasing and reversing the control valve on the completion of the power stroke of the plunger, whereby the flow of motive fluid is diverted from one end of the cylinder to the other end thereof and the return stroke of the plunger is occasioned by the energy of the motive fluid, and a valve shifting lever connected with the control valve and operable directly by the shoulder of the plunger as the latter approaches the limit of its return stroke, for moving said control valve to a neutral position and arresting the flow of the motive fluid, whereby the plunger is brought to a state of rest by cessation in the flow of the motive fluid.

In testimony whereof I have hereto signed my name this 15 day of August, 1925.

JOSEPH DE FRANCISCI.
